COUPLED CIRCUITS

Paul O. Farnham, Boonton, N. J., assignor, by
mesne assignments, to Radio Corporation of
America, New York, N. Y., a corporation of
Delaware

Application March 7, 1933, Serial No. 659,978

17 Claims.

(Cl. 178—44)

This invention relates to tuned transmission systems and particularly to methods of and circuit arrangements for coupling tunable circuits such as are used for the selective reception of radio waves.

It is well known that radio amplifiers embodying simple single tuned circuits in cascade designed to receive signals within a given frequency band by an adjustment of the tuning capacities of the several circuits do not exhibit uniform characteristics as regards amplification and selectivity at all frequencies to which the system may be tuned. The amplification generally rises as the system is tuned to the higher frequencies and at the same time the selectivity is decreased. Methods for obtaining both constant amplification and constant selectivity with single tuned circuits are described and claimed in my pending application Ser. No. 564,675, filed Sept. 20, 1931.

It is usually desirable in cascade amplification to use the tuned circuits in pairs for two reasons; (a) the required selectivity far from resonance is obtained without using an excessive number of vacuum tubes, and (b) the response to frequencies near resonance may be made substantially uniform in order to obtain fidelity in the transmission of the higher modulation frequencies. The coupling of two tuned circuits materially increases the difficulties presented by the problem of securing uniform gain and selectivity over the tuning band, particularly when each circuit is of the type in which the resistance is varied with the adjustable tuning element to maintain, for the individual circuits, a substantially constant gain and selectivity over the tuning range.

An object of the invention is to provide methods of and circuit arrangements for coupling tunable circuits, which methods and circuit arrangements are adapted to secure desired, and preferably approximately uniform, gain and selectivity characteristics over the entire tuning range. Another object of the invention is to provide, for use in connection with tunable circuits, coupling methods and circuits which permit the coupling ratio to be maintained at a desired value corresponding either to less than, equal to, or greater than critical shape coupling over the tuning range of the circuits. A further object is to provide, for use with inductance-tuned circuits, coupling methods and circuits which permit adjustment of the frequency band width of the response characteristic to any desired value within wide limits, the band width in frequency re-

maining constant over the frequency range for any given adjustment.

Fig. 1 is a fragmentary circuit diagram of a radio receiver, and illustrating an application of the invention to a coupled-circuit radio amplifier stage employing inductance tuning;

Fig. 2 is a curve sheet indicating the relative performance of circuits coupled in accordance with the invention, and similar circuits coupled by known methods; and

Figs. 3 to 7 are circuit diagrams illustrating alternative coupling arrangements.

The invention applies to coupled circuit systems, either inductance tuned or capacity tuned, which are composed of single circuits constructed in accordance with the disclosures in the aforementioned application; that is, to systems in which the ratio of inductance to resistance in each of the single circuits is maintained substantially constant with respect to tuning.

In the drawing, the reference numeral 1 identifies the tube of a radio amplifier stage which passes an amplified radio voltage to the succeeding tube or other load circuit through the coupled circuits I, II, each of which is inductively tuned to resonance at the frequency of a desired signal. The tuned circuits employed in such coupling system are usually of substantially identical construction and, for convenience of description and simplicity of analysis, the circuits I, II are assumed to be of this general type but it is to be understood that the invention is not limited to the coupling of two substantially identical circuits.

As shown in Fig. 1, each tuned circuit includes an adjustable inductance 2 for tuning the circuit to resonance, resistance 3 and a relatively fixed condenser 4 for alignment of the circuit. The junction of condensers 4 is connected to ground through the composite impedance, capacity 5 in series with a small inductance 6. The high potential terminal of circuit I is connected to the plate of tube 1 and the corresponding terminal of circuit II may be connected to the grid of the succeeding amplifier or detector.

The plate supply to the tube 1 may be completed through the inductance and resistance of circuit I by connecting the low potential terminal of resistance 3 to a plate current supply, indicated by +E_B, and grounding that terminal for radio frequencies by the condenser 7.

We may determine the type of coupling required for two such single circuits when constant gain and selectivity over the tuning range are desired for the resulting coupled circuits. The

ratio of the coupling coefficient to the power ratio of the circuit may be taken as the important criterion of coupling since it is this quantity which determines the shape of the frequency-response characteristic for a fixed tuning adjustment, as well as the transmission at resonance over the tuning range. For simplicity it will be assumed that the circuit inductances are equal as well as the resistances; in which case the following notation may be employed.

R=total series resistance of each tuned circuit.

L=inductance of circuit.

ω =angular frequency of impressed voltage.

$\eta=R/\omega L$ =circuit power ratio.

X_m =coupling reactance.

$k=X_m/\omega L$ =coefficient of coupling.

$K=k/\eta$ =coupling ratio.

Since we have assumed single circuits in which 20 R/L is constant over the tuning range, the power ratio η varies inversely as the first power of the frequency. Thus, in order to make the coupling ratio K constant with tuning, we must arrange that the coefficient of coupling k shall vary inversely as the first power of the frequency. It is to be noted that the elementary types of coupling reactance yield coupling coefficients which vary with an even power of the resonant frequency.

30 In accordance with the invention however, the coupling reactance is so designed as to obtain a coefficient of coupling that varies inversely as the first power of the resonant frequency and by this method the desirable result of constant gain and selectivity is obtained over the frequency band covered by the circuits.

40 The circuit of Fig. 1 illustrates a specific embodiment of the invention using inductance tuning and having variable resistances 3 which satisfy the primary requirement that L/R is constant. In the case of inductance tuning by means of iron cores movable with respect to the coils, the core design may conveniently be such that the inherent coil resistance serves as the variable resistance 3, since the coil resistance varies with the adjustment of the cores. By a proper design of the coupling reactance, condenser 5 in series with coil 6, a substantially constant coupling ratio 45 50 K=k/ η may be obtained in accordance with the previous discussion.

55 By selecting values of inductances of coil 6 and capacity of condenser 5 such that the coupling reactance becomes zero at a frequency somewhat higher than the highest frequency within the tuning range of the circuits, the coupling reactance will be capacitive and will vary only slightly from its correct value over the tuning 60 range of the circuits. The following example is given as illustrating the determination of specific values of the coupling elements in terms of the tuned circuit capacities and power ratio for the special case K=1.

65 Let C' =effective capacity of the coupling reactance

C'' =desired effective coupling capacity for $K=1$

C_m =capacity of condenser 5

$M=L$ =inductance of coil 6

$\phi^2=\omega^2 MC_m$

Then $C''=\phi B$, B is a constant (1)

75 $C''=C_m/(1-\phi^2)$ (2)

Setting (1) equal to (2) at two values of ϕ , say ϕ_1 and $\phi_2=A\phi_1$ we have:

$$\phi_1 B = \frac{C_m}{1-\phi_1^2} \quad 5$$

$$\phi_2 B = \frac{C_m}{1-\phi_2^2} \text{ or } A\phi_1 B = \frac{C_m}{1-A^2\phi_1^2}$$

Subtracting:

$$\phi_1 B(A-1) - \phi_1^3 B(A^3-1) = 0 \quad 10$$

which gives:

$$\phi_1 = \frac{1}{\sqrt{A^2+1}} \quad (3)$$

$$\phi_2 = \frac{A}{\sqrt{A^2+1}} \quad (4) \quad 15$$

For the desired tuning range from 550 to 1500 kc., letting $A=2$, and assuming ϕ_1 corresponds to 700 kc.:

$$\phi_1 = \frac{1}{\sqrt{7}} = .377 \quad 20 \quad (5)$$

$$\phi_2 = .754$$

series resonance of coupling elements occurs at 25 $\phi=1$ or at 700/.377=1860 kc.

Letting C =capacity of the tuned circuit I, C_m may be obtained in terms of C and the power ratio η of the tuned circuit at, say, 700 kc. where $K=1$ and $\phi_1=.377$.

$$K = \frac{C}{C'_{700}} \times \frac{1}{\eta_{700}} = 1$$

$$C'_{700} = \frac{C_m}{1-\phi^2} = \frac{C_m}{.858} \quad 35$$

Hence

$$\frac{C_m}{.858} = \frac{C}{\eta_{700}}$$

$$\text{or } C_m = C \times \frac{.858}{\eta_{700}} \quad (6) \quad 40$$

Also

$$M = \frac{1}{\omega^2 C_m} \text{ at } 1860 \text{ kc.} \quad (7)$$

Equations (6) and (7) thus give the required values of the coupling elements in terms of the 45 constants of the tuned circuits.

The curve 10 of Fig. 2 indicates the actual operation of the circuit when the coupling reactances have values corresponding to those determined by these equations. The curve 10 is 50 plotted between frequency and values of

$$\frac{C'}{C''}$$

where C' is the effective capacity of the coupling 55 reactance and C'' is the capacity which is required to satisfy the desired condition that the coupling ratio K remain constant and, under the particular conditions assumed, equal to 1.

It is obvious that the desired constant gain and 60 selectivity characteristics are obtained only for those frequencies at which the actual coupling capacity C' is equal to the required value C'' , and that there is a departure from constant gain and selectivity at frequencies for which the ratio 65 of the actual to the desired capacity is not unity. Curve 10 shows that the desired conditions were satisfied at 700 to 1400 kilocycles, i. e., at the frequencies assumed for ϕ_1 and ϕ_2 in computation 70 of the coupling reactances, and that the maximum departure of the actual capacity C' from the desired value, and hence the actual departure of the coupling ratio K from its desired value, is about 20%. Curve 11 indicates the variation of the actual coupling capacity from its desired 75

value when circuits I and II are coupled in the known manner by a simple capacitive coupling, i. e., when the corrective inductance G is omitted. Curve 11 was plotted for a value of $C' = C_m$ which was equal to the desired value C'' at 700 kilocycles. Curve 11 shows that the coupling at higher frequencies departs from the desired value by an amount considerably greater than that exhibited by a coupling circuit embodying the invention. Curve 12 indicates the performance of the coupled circuits when the value of a simple capacitive coupling is set at another value. Curves 11 and 12 clearly show that it is not possible to obtain even an approach towards uniform gain and selectivity when two tuned circuits, each having those characteristics, are coupled by the known capacitive couplings. The same argument applies to simple inductive couplings.

The circuit of Fig. 1 effects an electrical variation, with frequency, of the coupling reactance but the coupling coefficient may be varied mechanically by connecting an adjustable element of the coupling reactance to the shaft or adjustable tuning member.

As shown in Fig. 3, the tuned circuits I, II may each include a relatively fixed capacity C , a tuning inductance L and a variable resistance R ; the inductance and resistance of both circuits being simultaneously adjusted, as indicated by broken lines 9 which represent a mechanical interconnection of the adjustable elements, to maintain a constant gain and selectivity for the individual circuits. A variable coupling condenser C'_m is connected between the high potential terminals of the circuits, and the adjustable element of the variable condenser is connected to the gang control 9 through a mechanical connection 9'. With this arrangement, the adjustment of C'_m should be such that the coupling capacity varies inversely as the frequency. The input terminals of the first circuit are illustrated as connected to a conventional antenna structure A through the usual coupling condenser C_o , and to ground G, respectively. It is to be understood that each of the coupling systems herein illustrated may be employed as an interstage coupling between vacuum tubes, as a coupling between a collector structure and the first tube of a receiver system, or between other types of sections of a tuned alternating current transmission system.

As shown in Fig. 4, the tuned circuits I, II may be coupled by a variable condenser C_m which is connected between the ground terminals of the circuits and their respective high potential terminals through the condensers C_2 . The coupling coefficient is dependent upon the relative values of C_2 and C_m and, by mechanically connecting the coupling condenser to the tuning controls, C_m may be varied with frequency to obtain desired gain and selectivity characteristics. For constant gain and selectivity, C_m should vary directly with the frequency to keep K constant.

Mutual inductance M may be employed for coupling the circuits, as shown in Fig. 5, by so connecting the adjusting elements of the coupled coils 13 with the tuning controls that the inductance M varies inversely as the cube of the frequency when K is to remain constant.

The invention provides a simple and efficient method of obtaining substantially constant gain and selectivity when each of the coupled circuits is tuned by adjusting an iron core axially of the inductance. As shown in Fig. 6, each circuit includes a coil L shunting a relatively fixed tuning condenser C , and tuned by the adjustment

of an iron core 14. The resistances R which are shown as a series element of each circuit are not physical resistances, but the inherent resistances of the circuit which, as is well known, vary automatically with the tuning adjustment of the cores, and at such rate as to impart substantially constant gain and selectivity characteristics to the individual circuits. The low potential terminals of the circuit are connected to ground through the coupling condenser C_m , and the cores 10 are grounded, as indicated by leads 15.

The effective capacities C_3 between the coils and the cores serve to couple the circuits through the common capacity C_m . Capacities C_3 vary with the tuning and, as the cores are inserted into the 15 coils to increase the circuit inductance for lower frequencies, these effective capacities increase to provide the tighter coupling between the circuits necessary to maintain K constant. The advantage of this system lies in the fact that all elements necessary for varying the coupling coefficient in the proper manner are already provided in the structure of the tuning elements.

Although the system does not include mechanical connecting elements additional to those providing the gang tuning connection of the cores 14, as indicated by broken line 9, dotted lines 16 are shown as connecting the adjustable members of the resistances R and capacities C_3 to the gang control, thus indicating graphically that the values of these elements vary automatically with the tuning.

The circuit shown in Fig. 6 lends itself readily to an adjustment of the shape or useful band width of the selectivity curve. If the values are so chosen that the coupling ratio K is constant over the tuning range for one value of the coupling capacity C_m , the coupling ratio may be adjusted to a different but frequency-independent value by adjustment of the capacity C_m . The shape of the selectivity curve may therefore be changed to secure greater fidelity of transmitted side band frequencies, whenever local interference conditions permit, by adjusting C_m to a smaller value to obtain greater coupling corresponding to a higher value of the coupling ratio K . The value of K may be adjusted to correspond to critical coupling or to either less than or more than critical coupling, and the selected type of coupling will be maintained over the entire tuning range.

The inductances of the circuits shown in Figs. 1, 3, 4 and 5, may, of course, be varied by the adjustment of iron cores or by other means. When iron cores are employed, the resistances R are not physical elements but are the inherent resistances of the circuits.

The invention is equally useful with condenser tuned circuits and Fig. 7 shows a condenser tuned system using a coupling similar to that of the inductance tuned circuits of Fig. 3. Each circuit includes an inductance L , a tuning condenser C and a physical resistance R' which is mechanically connected to the tuning control, as indicated by broken line 9. The design and frequency adjustment of the resistance R' is such that the total series resistance R of the circuit varies to maintain L/R constant. The adjustable element of the coupling condenser C'_m is varied with tuning by a mechanical connection 9' to the tuning control. To maintain a constant coupling ratio K , the value of condenser C'_m must vary inversely as the cube of the frequency as the circuits are tuned over the frequency band.

The invention therefore provides a method of 75

coupling two circuits, each tunable by adjustment of the capacity or inductance of the circuit and each exhibiting a substantially constant gain and selectivity over the tuning range, to obtain 5 constant or substantially constant overall gain and selectivity. As indicated in the above discussion of the illustrated types of coupling systems, the exact variation of the coupling coefficient with frequency will depend upon the particular coupling method employed but, with any given type of coupling, the principles stated above will enable those familiar with this art to design the coupling reactance to provide the desired gain and frequency characteristics.

15 I claim:

1. In the operation of a transmission system including two tunable circuits coupled by a reactive coupling, the method of controlling the overall gain and selectivity characteristics of 20 the coupled circuits which comprises tuning each circuit to resonance at the desired frequency of transmission, varying the power ratio of each tuned circuit as an inverse function of the frequency, and simultaneously varying the reactance of the reactive coupling substantially as an even power of the frequency to which the circuits are tuned.

2. In the operation of a transmission system 30 including two tunable circuits coupled by a reactive coupling and each circuit including resistance, the method of controlling the overall gain and selectivity characteristics of the coupled circuits which comprises adjusting each circuit to resonance at the desired frequency of transmission, adjusting the resistance of each circuit simultaneously with tuning to maintain desired gain and selectivity characteristics for each circuit as it is tuned over its frequency range, and simultaneously varying the reactance 35 of the reactive coupling substantially as an even power of the frequency to which the circuits are tuned.

3. In the transmission of alternating currents by coupled circuits each of which is tunable 45 over a frequency range and includes resistance, the method which comprises tuning each circuit to the frequency of the currents to be transmitted, varying the resistance of each circuit with tuning to maintain approximately constant 50 gain and selectivity characteristics for the separate circuits, coupling the circuits with a reactive coupling to obtain a desired coupling ratio at one transmission frequency, and varying the coupling coefficient with tuning and substantially inversely as the first power of the 55 frequency to which the circuits are tuned.

4. In the transmission of alternating currents by coupled circuits each of which is tunable over 60 a frequency range and includes resistance, the method which comprises tuning each circuit to the frequency of the currents to be transmitted, varying the resistance of each circuit with tuning to maintain approximately constant gain and 65 selectivity characteristics for the separate circuits, coupling the circuits with a reactive coupling to obtain a desired coupling ratio at one transmission frequency, and varying the reactance of the reactive coupling with tuning and substantially as an even power of the frequency 70 to which the circuits are tuned.

5. In an electrical transmission system, the combination with two circuits serially arranged in the direction of transmission and each tunable 75 over a frequency band, means for tuning

said circuits simultaneously to the desired frequency of maximum transmission within said band, and means operative with said tuning means for suppressing variations of the gain and selectivity characteristics of the separate 5 circuits, of means for suppressing variations of the overall gain and selectivity characteristics of said circuits as the latter are tuned over the frequency band, said last means comprising a reactive coupling between said circuits. 10

6. A transmission system as claimed in claim 5, wherein said reactive coupling comprises an inductance-capacity network having a capacitive reactance throughout the tuning range of said circuits. 15

7. A transmission system as claimed in claim 5, wherein said reactive coupling comprises a complex reactance having, throughout the tuning range of said circuits, a capacitive reactance that approaches zero at a frequency above the 20 highest frequency in said tuning range.

8. In an electrical transmission system, two circuits tuned to substantially the same frequency, each circuit including resistance and reactances of opposite signs, similar reactances 25 of the two circuits being adjustable to tune the circuits over a frequency band, reactive coupling between said circuits, means operative upon adjustment of said similar reactances to vary the power ratios of said circuits to suppress 30 variation of the gain and selectivity characteristics of the separate circuits, and means for varying the coefficient of coupling with tuning and substantially inversely as the first power 35 of the frequency to which the circuits are tuned. 35

9. An electrical transmission system as set forth in claim 8, wherein a mechanical connection is provided between the adjustable reactance of said circuits for simultaneously adjusting the same to tune said circuits, and said reactive coupling includes a reactance having an adjustable element mechanically connected to 40 said mechanical connection.

10. A transmission system as set forth in claim 8, wherein the said similar adjustable reactances 45 of said circuits comprise inductances and grounded iron cores adjustable with respect thereto to tune said circuits, and said reactive coupling includes a capacity common to said circuits and in series with the inherent capacities between 50 the cores and inductances of the separate circuits.

11. In an electrical transmission system, the combination with two circuits each tunable over a frequency band and each having approximately 55 constant gain and selectivity characteristics, of means coupling said circuits in cascade, and means adapted to maintain approximately constant overall gain and selectivity characteristics for said cascaded circuits, said last means 60 including means for varying the coefficient of coupling between said circuits with tuning and approximately inversely as the first power of the frequency to which said circuits are tuned. 65

12. In an electrical transmission system, the combination with two circuits each tunable over a frequency band and each having approximately constant gain and selectivity characteristics, of adjustable means reactively coupling said circuits in cascade, said coupling means being manually 70 adjustable to obtain critical shape coupling or either more or less than critical coupling between said circuits when the latter are simultaneously tuned to the same frequency, and means for automatically varying the reactance of said 75

coupling means with frequency to maintain throughout the tuning range that shape of coupling determined by the manual adjustment made at one frequency and simultaneously therewith to maintain approximately constant overall gain and selectivity characteristics for said cascaded circuits.

13. In an electrical transmission system, the combination with two tuned circuits each including resistance and reactances of opposite types, and means for simultaneously adjusting one reactance of each circuit to maintain said circuits continuously in resonance when tuned over a frequency band, of means for adjusting the resistance of each circuit with tuning to maintain a constant ratio between the resistance and inductance of the individual circuits, means reactively coupling said circuits, and means automatically varying the reactance of said coupling means with frequency to maintain a substantially constant coupling ratio throughout the frequency range, said automatic means varying the coupling coefficient approximately inversely as the first power of the frequency to which said circuits are tuned.

14. An electrical transmission system comprising a pair of circuits including substantially identical inductances shunted by substantially identical capacities, iron cores adjustable with respect to said inductances, means connecting said cores for simultaneous adjustment to maintain said circuits continuously in resonance when tuned over a frequency band, means grounding said cores, and a common capacity connected between ground and the low potential terminals of said circuits, whereby said circuits are coupled through said common capacity and the capacities between the cores and inductances of the individual circuits.

15. In an electrical transmission system the combination with two circuits serially arranged in the direction of transmission, each of said circuits being tunable over a frequency band, means for tuning said circuits simultaneously to the desired frequency within said band and means operative with said tuning means for suppressing variations of the gain and selectivity characteristics of the separate circuits, of means for suppressing variations of the overall gain and selectivity characteristics of said circuits as the latter are tuned over the frequency band, said last-named means comprising a reactive coupling between said circuits arranged so that the coupling reactance thereof becomes zero at a frequency which is somewhat higher than the highest frequency of the tuning range.

16. In an electrical transmission system the combination with two circuits serially arranged in the direction of transmission each of said circuits being tunable over a frequency band, means for tuning said circuits simultaneously to the desired frequency within said band and means operative with said tuning means for suppressing variations of the gain and selectivity characteristics of the separate circuits, of means for suppressing variations of the overall gain and selectivity characteristics of said circuits as the latter are tuned over the frequency band, said last-named means comprising a reactive coupling between said circuits variable simultaneously with the variations in tuning of said circuits.

17. A transmission system as claimed in claim 16 wherein said reactive coupling comprises a capacity arranged with respect to the tuning means of said circuits so that the capacity value thereof varies inversely with the frequency to which the tuning circuits are tuned.

PAUL O. FARNHAM.
